UNITED STATES PATENT OFFICE.

AMBROSE TANSLEY AND WILLIAM H. RUSSELL, OF LOS ANGELES, CALIFORNIA.

AUTOMOBILE-FENDER.

1,233,727.

Specification of Letters Patent. Patented July 17, 1917.

Application filed January 8, 1916. Serial No. 71,131.

To all whom it may concern:

Be it known that we, AMBROSE TANSLEY and WILLIAM H. RUSSELL, citizens of the United States, residing at Los Angeles, in 5 the county of Los Angeles and State of California, have invented a new and useful Automobile-Fender, of which the following is a specification.

This invention relates to fenders and the 10 object of the invention is to provide a device which may be fastened at the front of the automobile, and so constructed as not to interfere with the operation of, or detract from the appearance of the said automobile, 15 yet efficient in the discharge of a duty which fenders are supposed to render. Other objects and advantages will be brought out in the following description.

Referring to the drawings:

20 Figure 1 is a side view, Fig. 2 a plan, and Fig. 3 a front view. Figs. 3 and 4 show the fender in open and closed positions, respectively as applied to an automobile. 1, 1 25 designate the forks of the fender which are clamped upon the front springs of the automobile and 7, 15, 15 designate rods for joining the two forks rigidly together upon one of which is attached one end of the equalizing bar 10' Fig. 2. The other end of the 30 equalizing bar 10' is attached to the sleeve 16' which slides upon the hinge rod 13. One end of the equalizing bar 10' is securely fastened to the hinge bar 13 and the other to a sliding sleeve 12 which slides upon the two 35 joining rods 15' and 15'. The two equalizing bars 10' and 10' are joined at their intersection by the pin 17 which permits of a working joint.

The two sections comprising the fender, 40 are hinged together at one of their longitudinal sides by the hinge rod 13 and by the steel straps 5 which form the finished construction of the fender. 18' and 18' are 45 rods forming the outer horizontal sides of the two sections respectively and to which the other ends of the steel straps are securely fastened. The guide rods 8' and 8' of the upper section and 8' and 8' of the lower section are also hinged upon the hinge rod 13 50 at one of their ends and rigidly fastened to the outer frame rods 18' and 18' at their other ends respectively and which, said 55 guide rods are at right angles to the hinge rod 13 and to the outer frame rods 18' and 18'. These guide rods work freely through their respective guides 4' 4' 4' 4', said guides

being free to revolve upon their respective bearings 14' 14' 14' 14', and which are situated at the points of the two forks 1 and 1.

The trip rod 6 is held in place in front 60 of the hinge of the two sections by the bolts 19' and 19' which pass loosely through the hinge rod 13 and fasten securely in the trip rod 6. The springs 9' and 9' keep the trip rod under a tension; the heads of the two 65 bolts 19' and 19' limiting the outward travel of the trip rod.

The catch rod 3' is attached to the center of the trip rod 6 at one end and hinged to the catch 3' at the other.

The catch 3' is hinged at its center to the rod 3' and also to the outer frame rod 18' and said catch engages with the joining rod 15' when the two sections are closed as in Fig. 1, locking the sections in that position.

The catch 2 engages with the equalizing bar 10' when the two sections are open as in Fig. 5 securely holding the sections in that position. 11 designates a flat spring one end 80 of which is rigidly fastened to the fork 1, the other end is joined to the intersection of the equalizing bars 10' and 10' by the two links 20' and 20'.

A wire 21 running from the magneto of 85 the automobile to the contact piece 22 said contact piece being insulated from the frame of the fender and so placed that when the two sections are open as in Fig. 4 the moving part of the fender will make contact 90 with the contact piece 22.

Operation.

The trip rod 6, in coming in contact with a body, is moved rearward; the movement 95 is communicated to the catch rod 3' which in turn communicates the movement to the catch 3'. The catch will then be disengaged from the joining rod 15' which permits the two sections to take the position as shown 100 in Fig. 4 through the medium of the spring 11, which being under a sufficient tension pulls upon the intersection of the equalizing bars 10' and 10', and they, being attached to the hinge rod 13 at two of their ends 105 and to the frame of the fender, or joining rods, at the other ends, the hinge of the two sections moves in a straight line toward, and between the two points of each fork, being guided by the equalizing bars, the guide 110 rods and guides. The guides 4' 4' 4' 4' being held at the points of their respective

forks, by their respective bearings 14', 14², 14³, 14⁴, the guide rods 8', 8², 8³, 8⁴ slide through their respective guides as the hinge of the sections moves toward the center; the guides turning upon their bearings. The 5 guides turning upon their bearings. The equalizing bars prevent one of the sections from moving faster than the other by holding the hinge centrally, as well as distributing the pressure of the spring 11 equally 10 upon the bearings of the two forks.

As the two sections take the position as shown in Fig. 4, the equalizing bars take a position parallel to each other, and as one of the ends of each of said bars 10' and 10² 15 is fastened in a stationary position to their respective parts 13 and 15, the other ends of said equalizing bars must move in a circular path, their opposite ends forming the center of said path.

Since the hinge of the two sections moves in a straight line laterally as well as horizontally, and two of the ends of the equalizing bars are stationary, then the ends of the equalizing bars which are attached to 20 the sleeves 16' and 12 must permit the hinge rod 13 to slide freely in said sleeve 16', and sleeves 12 to slide freely over the joining rods 15' and 15². When the two sections are 25 open as in Fig. 4, the equalizing bar 10² engages with the catch 2 which being securely attached to the fork 1, holds the sections in 30 that position.

At the moment the fender is thrown open the moving part of the fender comes in contact with the contact piece 22, which causes 35 the magneto of the automobile to become shorted, thus preventing a spark at the engine. The automobile then, can not be run until the fender is again closed. The 40 automobile is automatically stopped, thus preventing the driver from making his escape.

The advantages of this fender are obvious, in the first place the fender will assume instantaneously such position as to completely shield 45 the body struck, from the machine, as well as protecting the lights and other parts of the automobile from the body struck; the fender has an attractive appearance owing to its stream line effect, when closed, and is 50 placed sufficiently high to prevent interference with the operation of the said automobile; the lowest part of said fender not being lower than the axle of said automobile.

What I claim is:

55 1. An automobile fender comprising two

sections and hinged together at one of their longitudinal sides; said sections being held under a tension by means of a spring and catch; said catch operated by means of a trip; said trip releasing said spring when 60 said fender collides with a body; said fender receding from said body while assuming automatically an operative position, and simultaneously short circuiting the magneto of the automobile upon which said fender 65 is placed.

2. An automobile fender comprised of two sections; hinged together at one of their longitudinal sides and held in operative position under a spring tension at an 70 acute angle upon a frame; said sections being held by means of a catch; said catch operated by a trip means placed at the apex of the two sections forming the said acute angle; said sections automatically assuming an operative position when said trip releases said spring; said trip releasing said spring when said fender collides with a body; said fender receding from said body while assuming said operative position; 80 means to lock itself in said operative position, and means to simultaneously short circuit the magneto of the automobile upon which said fender is placed.

3. An automobile fender comprised of two 85 sections, hinged together at one of their longitudinal sides and held under a spring tension at an acute angle upon a frame; said sections being held by means of a catch; guide means attached to said frame, and 90 guide rods attached to the two sections; said catch operated by a trip bar placed at the apex of the two said sections forming said acute angle, and running parallel to their longitudinal sides; said sections automatically assuming an open position when said fender collides with a body, and receding from the body struck while assuming said open position; means to lock itself in said open position, and means to simultaneously 100 short circuit the magneto of the automobile upon which said fender is placed.

In testimony whereof, we have hereunto set our hands at Los Angeles, California January, 1916.

AMBROSE TANSLEY,
WILLIAM H. RUSSELL.
